UNITED STATES PATENT OFFICE.

JAMES W. HORN, OF ARBA, INDIANA.

DETONATING BURGLAR-ALARM.

SPECIFICATION forming part of Letters Patent No. 530,947, dated December 18, 1894.

Application filed September 29, 1894. Serial No. 524,486. (No model.)

To all whom it may concern:

Be it known that I, JAMES W. HORN, a citizen of the United States, residing at Arba, in the county of Randolph and State of Indiana, 5 have invented a new and useful Burglar-Alarm, of which the following is a specification.

The invention relates to improvements in burglar alarms.

10 The object of the present invention is to improve the construction of burglar alarms, and to provide a simple and inexpensive device, adapted to be readily applied to a window sash, and capable of exploding a cap in 15 the event of an attempt to raise the sash.

A further object of the invention is to provide such a device, in which the parts will be compactly arranged, and protected, and not liable to get out of order, or become broken.

20 The invention consists in the construction and novel combination and arrangement of parts hereinafter fully described, illustrated in the accompanying drawings, and pointed out in the claim hereto appended.

25 In the drawings:—Figure 1 is a perspective view of a burglar alarm constructed in accordance with this invention. Fig. 2 is a transverse sectional view of the same, showing the burglar alarm applied to a window in 30 position to be engaged by the lower sash. Fig. 3 is a longitudinal sectional view.

Like numerals of reference indicate corresponding parts in all the figures of the drawings.

35 1 designates a tubular casing designed to be mounted on the upper sash of a window, and provided at one side with a longitudinal opening or slot 2, communicating with the longitudinal bore, and receiving an arm 3 of

40 a spring actuated hammer 4 adapted to explode a cap. The hammer 4 is rounded to conform to the configuration of the bore of the tubular casing, and its rear end is engaged by a spiral spring 5, which bears against 45 a plug 6 fitted in one end of the casing, and secured to the same by a screw 7, which also serves as the means for attaching the device to the upper sash 8 of the window.

The casing is provided at the lower side of

the longitudinal slot 2 with a notch 9, which 50 receives the arm 3 when the hammer is moved rearward against the action of the spring, for the purpose of setting the device; and the arm 3 projects outward from the upper sash sufficiently to be engaged by the lower sash, 55 should the latter be raised. The lower sash in raising lifts the arm 3 out of engagement with the notch 9, and the spiral spring throws the hammer forward into engagement with a cap-holding plug or block 10. 60

The cap holding plug or block 10 is round, to conform to the configuration of the casing, and it is provided at its inner end with a nipple-shaped projection 11, adapted to receive an ordinary percussion cap, which is 65 placed on the projection after the block or plug has been removed. The block or plug is provided with a transverse perforation 12, which receives a removable key or pin 13, passing through registering openings 14 of 70 the casing.

It will be seen that the burglar alarm is simple and comparatively inexpensive in construction, that it is adapted to be readily applied to a window, and that the parts are compactly arranged and concealed within the tubular casing. 75

It will also be apparent that the device may be readily arranged adjacent to a door, or the like, in position to be discharged by the opening of the door. 80

Changes in the form, proportion, and the minor details of construction may be resorted to without departing from the principle or sacrificing any of the advantages of this invention. 85

What I claim is—

A burglar alarm, comprising a tubular casing, having at one side a longitudinal slot and provided at the bottom of the same with a 90 notch, a plug arranged within one end of the casing, a fastening device passing through the casing and the plug and serving as the means for securing the device to a window or the like, a hammer arranged within the casing 95 and conforming to the configuration thereof, and provided with an arm located in the slot of the casing and adapted to engage the

notch, a spiral spring located within the casing and interposed between the plug and the hammer for actuating the latter, a removable plug or block fitted in the casing at the other end thereof and provided at its inner end with a cap receiving projection, and a pin or key passing through the casing and the block or plug, substantially as described.

In testimony that I claim the foregoing as my own I have hereto affixed my signature in the presence of two witnesses.

JAMES W. HORN.
